UNITED STATES PATENT OFFICE.

ADOLF ELEFANT, OF LOS ANGELES, CALIFORNIA.

WINDOW-SHUTTER.

1,071,220.

Specification of Letters Patent. Patented Aug. 26, 1913.

Application filed May 4, 1912. Serial No. 695,312.

To all whom it may concern:

Be it known that I, ADOLF ELEFANT, subject of the Emperor of Austria-Hungary, residing at Los Angeles, in the county of 5 Los Angeles and State of California, have invented a new and useful Improvement in Window-Shutters, of which the following is a specification.

My invention relates to improvements in 10 window shutters, and the object of my invention is to provide a shutter that may be easily rolled up or down, with open or closed slats, and which may be extended and locked in a slanting position from the window. I 15 attain this object by means of the mechanism illustrated in the accompanying drawings, in which—

Figure 1 is a rear elevation of the shutter closed. Fig. 2 is a cross sectional view of 20 Fig. 1 on the line X'—X'. Fig. 3 is a broken view of one corner of the shutter and casing showing the slats drawn apart. Fig. 4 is a sectional view of Fig. 3 on line 25 X²—X². Fig. 5 is a similar view to Fig. 3 showing the shutter slats closed. Fig. 6 is an enlarged detail view of the ratchet belt wheel and the locking lever. Fig. 7 is an enlarged detail view of the extension arm. Fig. 8 is a side view of Fig. 7. Fig. 9 is a 30 view showing a cranking method of turning the ratchet wheel.

My shutter is composed of a plurality of slats adjustably attached to linked bands adapted to carry the shutter to and around 35 a roller at the top of the window casing. The slats 13, may be made of wood or of metal and of any desired width. They are secured to the linked bands 12, by means of the pins, 14, on the band engaging the slots 13' in the slats. These slots allow enough play to cause the slats to separate and leave an open space between them when partly drawn up. The linked bands, 12, have the upper ends secured to the roller 3, in the 45 roller box 2, the said roller being journaled in the bearings 5 in the casing 1 by the pins 4. On one end of the roller 3 is fixed the drum 6, on which is reeled the belt 7. This belt runs over the roller 6' on the inside 50 face of the casing and down the casing to the plate 8, and through the slot 9 in said plate to the drum 18, which is provided with the ratchet 19. The locking lever 20, whose

pawl 20' is adapted to engage the ratchet 19 is designed to normally lock the ratchet 55 wheel from back movement. By depressing this lever the ratchet is unlocked and the belt released to run upward, and allow the shutter to slide downward. When drawn up by pulling down on the belt 7, 60 the slats separate leaving openings between them. When let down the tongues 22 engage the grooves 21 and close the shutter slats.

The shutters are confined in the grooved 65 frame 12' which fills the window casing movably and is hinged at 23, and the whole shutter may be extended from the hinge 23 outward and held locked in that position by means of the extension arm 15, which is 70 hinged at its ends to the bottom of the shutter frame and the casing respectively, and locked by the knuckle joint 16, the crank handle 17 being used to extend and lock the arm.

As shown in Fig. 9, instead of pulling on the belt 7, I may use the crank 29 on the crank shaft 26 in the bearings 27, and on which is formed the pinion 28 adapted to engage the gear 25 on the drum. 75

The shutter may be pulled entirely or partly up, or let entirely down at will, and locked by the locking lever 20, and the locking hook 24 and the slats of the shutter opened or closed by a short pull or loosening of the friction belt 7 respectively. These slats fitting together in a notched tongue and groove manner make the shutter fire proof and wind proof as well as light proof. The provision for extending the bottom of 90 the shutter out from the casing allows the entrance of air and light while shading the window from sunlight and storms.

What I claim as my invention and desire Letters Patent for, is—

In a window shutter the combination with a frame, of a plurality of slats slidably mounted on a link band in said frame, means for connecting said slats with said band, and means for slidably regulating the 100 openings between said slats.

ADOLF ELEFANT.
